FLUID-COOLED TUBE FOR SIGHTING A
FURNACE PYROMETER

Emil Jantsch, Youngstown, Ohio, assignor to Carnegie-Illinois Steel Corporation, a corporation of New Jersey

Application July 11, 1945, Serial No. 604,409

14 Claims. (Cl. 257—254)

1

This invention relates to a cooled tube adapted for mounting in high temperature apparatus, and characterized by a novel, simple, and efficient cooling means.

The invention has among its objects the provision of an improved water-cooled pyrometer tube for furnaces and the like.

A further object of the invention resides in the provision of a jacketed heat exchange device, such as a water-cooled pyrometer tube, so constructed that heat exchange takes place uniformly throughout its extent, that it may be easily disassembled for cleaning whereby it is simple to maintain, and that it will have a long service life.

These and other objects of the invention will be made more fully apparent in the following description.

The device of my invention because of its simplicity, ease of maintenance, and uniformity of heat transfer is capable of use to advantage in a variety of applications requiring the transfer of heat, and it may be made in a variety of shapes, depending upon the use to which it is put. For the sake of simplicity it will be described, however, in that modification in which it is tubular in shape. Although the tube is herein-after spoken of as a water-cooled tube, it may in some instances be employed so that the flow of heat is reversed and the tube is heated rather than cooled. Furthermore, fluids other than water may be employed as the cooling agent. The tube is illustrated and described herein, however, in connection with its use as a water-cooled pyrometer tube on a furnace, in which use it displays perhaps the maximum advantages.

In high temperature heating furnaces, such as those for heating steel billets, the temperature of the billets is measured by means of a radiation pyrometer trained through a furnace opening upon the billets in the final heating zone. In the interests of accuracy of the measurement of such temperature, it is necessary to choose the line of sight of the pyrometer as short as possible and to maintain such line of sight free from opaque gases. For this reason, there is customarily employed a pyrometer tube extending into the furnace in close proximity to the articles whose temperature is to be measured. As a consequence, the inner end of the tube is subjected to very high temperatures, which in the case of a reheating furnace may be in the order of 3000° F. In order to give the pyrometer tube as long a life as possible in such extreme conditions of service, it has been customary to cool

2

the tube by means of a water jacket. Such prior water jacketed pyrometer tubes have not been entirely satisfactory however, since they have been prone to local overheating with resultant steam binding and have frequently caused the creation of a fog within the tube in the line of sight by reason of the cooling of the inner surface of the tube below the dew point of the gas within it.

10 The pyrometer tube of my invention overcomes the difficulties above outlined, and is also more easily maintained and serviced than prior pyrometer tubes. It comprises a water-cooled tube having means whereby the cooling water is caused to flow uniformly into contact with every portion of the tube surface. Means are provided whereby the cooling water flows first in one direction and then the other along a tube through metered inlet and outlet ports, the 20 water being so baffled as to flow mainly in lines parallel to the axis of the tube. There is further provided a novel means for purging the atmosphere in the sight line in the tube and removing the condensate therefrom so that such atmosphere 25 is caused to follow a definite path and is positively removed. As one of the preferred embodiments of the invention, there is further provided means whereby a mixture of air and water may be employed as a cooling medium, and whereby the mixture is agitated in the desired 30 degree to accomplish optimum cooling.

The invention will be more readily understood by reference to the accompanying drawings, in which:

Figure 1 is a view in vertical section longitudinally through a billet reheating furnace employing the pyrometer tube of the present invention;

Figure 2 is a view in vertical section through a pyrometer tube made in accordance with the present invention;

Figure 3 is a view in horizontal cross section, said section being taken along the line III—III of Figure 2;

Figure 4 is a view in horizontal cross section through the pyrometer tube taken along the line IV—IV of Figure 2;

Figure 5 is a view in horizontal cross section through the pyrometer tube taken along the line V—V in Figure 2;

Figure 6 is an enlarged partial vertical section of the lower end of the pyrometer tube shown in Figure 2;

Figure 7 is a view in vertical section through the upper portion of a modified pyrometer tube

made in accordance with the present invention;

Figure 8 is a view in horizontal section taken along the line VIII—VIII of Figure 7;

Figure 9 is a view in horizontal section through the lower portion of a still further modification of the pyrometer tube;

Figure 10 is a view in horizontal section through the lower portion of a third modification of the pyrometer tube;

Figure 11 is a broken out view partially in vertical section of another modification of the tube, employing a helically corrugated dividing tube;

Figure 12 is a similar view of a modification employing a dividing tube provided with sinusous corrugations;

Figure 13 is a view partly in vertical section of the lower end of a modified tube employing insulation upon the outer and lower surfaces thereof; and

Figures 14 and 15 are somewhat schematic views in vertical and horizontal section, respectively, through a pyrometer tube made in accordance with the present invention illustrating the manner of flow of the cooling fluid through the inner and outer cooling spaces.

The billet reheating furnace 2 shown in Figure 1, in which the pyrometer tube is illustrated, is of the conventional type in which a series of billets 4 move progressively down the inclined hearth 6 from the cooler charging zone to the hotter finish heating zone, billets heated to the desired temperature being sequentially discharged from the furnace by being pushed out the side door shown. The temperature of the billets in the finish heating zone is measured by means of the pyrometer 10 mounted on pyrometer tube 12 which in turn projects through the furnace roof 8 so that its inner end is close to the surface of the billets. Radiation pyrometer 10, which generates an electric current commensurate with the temperature of the article upon which it is trained, is connected to the recording device 14 so that a record of the temperature of the billets ready to be discharged is continuously available. Such pyrometer may be one of various commercially available radiation pyrometers of the thermo-couple type of which that sold under the trade mark "Rayotube," made and sold by the Leeds and Northrup Co., Philadelphia, Pa., is typical. Such pyrometer is of the lens type radiation pyrometer focusing upon a thermopile, and generating 7.8 millivolts at 2600° F. temperature with a focal length of 24 inches and over.

The pyrometer tube 12 in the embodiment shown in Figures 2 to 6, inclusive, consists of a double walled tube, the outer wall or barrel 16 of the tube being connected to the inner wall 18 at the bottom of the tube by the semi-toroidal portion 17. The outer wall 16 is provided at its upper end, at a point above the upper surface of the roof of the furnace, with a flange 20 and somewhat below the flange but above the roof with a volute inlet manifold 22 connected with the inlet pipe 24 which supplies the cooling fluid to the pyrometer tube. The outer wall 16 of the tube is provided with a series of equally spaced holes or ports 26 within the manifold 22 to admit cooling fluid thereto from the manifold, the design of the manifold being such that its cross sectional area progressively decreases from the location of the inlet pipe 24 to a point diagonally opposite so that equal volumes of water under equal pressures are admitted through the tube through each of holes 26 regardless of its location.

Carried upon the upper surface of flange 20 is an integral expansion joint 28, the bottom flange 30 of which is secured to flange 20 by bolts as shown and sealed therewith by means of an interposed packing. Joint 28 is generally tubular in shape to form an extension of outer wall 16 of the tube and consists of a lower flexible diaphragm 32 having an S-shaped cross section and an upper flexible diaphragm 36 of a reversely curved S-section, diaphragms 32 and 36 being joined by an intermediate right circular cylindrical wall portion 34. Attached to diaphragm 36 is a top flange 38 to carry the upper elements of the pyrometer tube, such as the end closing means and the optical apparatus, and to seal it therewith. Diaphragms 32 and 36 of joint 28 are made sufficiently flexible to accommodate the elongation of the outer tube wall 16 relative to the inner tube wall 18 when the pyrometer tube is in service and to maintain a sealed joint in spite of such flexure.

The cylindrical wall 34 of joint 28 is provided with a volute exit manifold 40 connected to the outlet pipe 42 for the cooling fluid from the pyrometer tube, there being a series of spaced holes or ports 44 through the circular cylindrical wall 34 within the manifold. The manifold 40, as in the case of manifold 22, is so designed that an equal volume of water at the same pressure flows out through each of the holes 44, thereby insuring in conjunction with the uniform ingress of cooling fluid at circumferentially spaced portions of the tube, uniform cooling of the tube circumferentially thereof.

Attached to flange 38 of joint 28 is a head 46 closing the outer end of the pyrometer tube, which is in the form of a circular plate 48 having a hollow centrally located upstanding nipple 52 thereon. Plate 48 is bolted to and cooperates with flange 38 through the medium of an interposed packing to seal the upper end of the water jacket of the pyrometer tube, the inner wall 18 of the tube being threaded into the central threaded opening 50 in plate 48. A housing 54 enclosing an optical system and providing a mounting for a series of lenses, is screwed to the threaded upper portion of nipple 52.

For the purpose of removing opaque gases, such as smoke and fumes from the furnace from the interior of the pyrometer tube, there is provided an opening for the introduction of gas such as compressed air into the interior of the upper portion of the tube so that the purging gas will travel downwardly through the bore of the tube. Such opening may take the form of a diagonal bore 56 in the optical mounting 54, a nipple 58 being screwed thereinto and being connected to a pipe 60 for supplying the purging gas under pressure. Gas so introduced travels downwardly through the bore of the tube carrying with it furnace gases which may have traveled into the tube. Some of such purging gas mixed with the gases to be removed tend to be heated by contact with the inner wall of wall 18 and thus to travel upwardly therealong. Such rising gas is removed from the tube without again traveling to the axis thereof to obscure the sight line by being trapped under the overhanging ring or flange 62 in nipple 52, from which it is led to the atmosphere through one or more openings 64. When the pyrometer tube is mounted in an upright substantially vertical position, as shown in Figure 1, ring 62 functions to trap gases rising along the inner surface of the wall 18 and to lead them out through hole 64. The pyrometer

may, however, be mounted in various positions including that in which it is upside down and substantially vertical. In such case, ring 62 functions to collect condensate which may trickle down the inner surface of wall 18, such condensate flowing from the inner concave surface of the ring out the hole or holes 64, such flow being aided by the pressure of the purging gas.

To insure the travel of the cooling fluid the full length of the pyrometer tube and its return over the same length of travel as well as to govern flow of such fluid circumferentially of the tube, there is provided an intermediate dividing tube or baffle between the walls 16 and 18. In the modification shown in Figure 2, such dividing tube 66 is made in the form of a prolongation of the cylindrical wall portion 24 of the expandable element 28. Tube 66 may be conveniently made separately and subsequently welded to the bottom portion of the wall 34. As shown in Figure 4, dividing tube 66 is provided in the vicinity opposite the inlet manifold 22 with a plurality of equally spaced corrugations 68 parallel to the axis of the tube, such corrugations being sufficient in number and so spaced relative to the holes 26 as to divide the cooling space between the outer tube 16 and the dividing tube 66 into a plurality of equal chambers symmetrically located with respect to holes 26. Corrugations 68 are continued to the bottom of tube 66, said tube reaching to a point near, but somewhat spaced from the end 17 of tube 16 as shown in Figure 6. Thus the flow of water in such outer cooling space, the flow in the preferred modification being directed downward, takes place in a plurality of zones of equal extent, the water in each zone being of the same volume and having the same velocity. In order to insure further complete uniformity of cooling in such outer zone, the lower portion of dividing tube 66 extending from the point 74 opposite the point 72, at which the inner wall 18 is offset to provide a larger diameter in the lower portion thereof, is provided with a plurality of shorter corrugations 78 intermediate each of the long corrugations 68. The structure of the dividing tube 66 at such lower portion is more clearly shown in Figure 5. Corrugations 70, which with corrugations 68 are equally spaced circumferentially of tube 66, are preferably somewhat more shallow than the radial distance between the inner and outer walls of walls 16 and 18, respectively, as are corrugations 68 below the point 74, so that narrow passages exist between such corrugations and the walls, thereby allowing equalization of flow between such smaller divisions of the cooling space. In the main, however, it will be evident that the flow of cooling water within such smaller divisions will be in a direction axially of the tube.

Water thus fed downwardly in the outer cooling zone between the outer hotter wall 16 and the dividing tube 66 flows around the lower end of the dividing tube as shown in Figure 6 and progressively upwardly in contact with the inner cooler surface of wall 18 until it flows out of holes 44 into the outlet manifold 49. Flow of the water in such inner cooling space will likewise be mainly in an axial direction due to the restraint imposed upon it by the rear surfaces of the corrugations 70 and 68, and for this reason flow and therefore cooling in such inner space will likewise be uniform. It is preferred that the direction of the cooling fluid be as shown in Figure 2, in which the fluid enters manifold 22, flows downwardly in the outer cooling space and upwardly in the inner cooling space. Such direction of flow

allows the cooling fluid to be sufficiently heated by its flow in the outer cooling space so that it is at a temperature above the dew point of the gases within the pyrometer tube when it comes into contact with the inner wall 18. Thus there is no danger, as there would be if the cooling water were first introduced into contact with the inner wall 18, that moisture will condense upon the inner surface of the tube and tend to form steam, thereby obscuring the sight line.

As shown in Figure 3, there are provided a plurality of equally spaced radial projections 76 on the inner surface of wall 18, such projections being of short axial extent to prevent disturbing the uniformity of flow of the cooling fluid into the exhaust manifold. Similar radial projections 78 are provided on the dividing tube 66 as shown in Figure 4 so that the dividing tube is maintained in concentric relationship with the inner wall 18 of the pyrometer tube. The lateral projections 76 and 78 function as baffles so as to cut down the tendency of the fluid to flow circumferentially of the spaces within which they are located, and thus aid in the maintenance of uniform flow at the same velocity of the fluid through the compartments and sub-compartments of the tube.

In Figures 7 and 8 there is shown a modification of the pyrometer tube previously described, the main differences lying in the type of expansion joint provided between the inner and outer walls of the tube and in the means for supplying the cooling medium to the tube, whereby such medium may be agitated or its character modified as desired. In Figures 7 and 8, parts of the pyrometer tube, which are the same as those of the tube shown in Figures 1 to 6, inclusive, are designated by the same reference characters with an added prime. In the structure shown in Figures 7 and 8, the part interposed between the upper end of the outer wall 16' and the part 52' supporting the optical mounting 54' is not rigidly attached to such outer wall but is made slidable therein. Thus, sleeve 80, which is integral with the outlet manifold 49', is provided on its lower end which extends within the upper end of wall 16' with a flange 82 carrying a packing 84 which forms a seal between the sleeve and the outer tube wall, said packing being held under compression by a gland means subsequently to be described. The dividing tube 66' is attached to the lower surface of flange 82 so as to make a fluid tight connection, as by being welded thereto.

The lower end of nipple 52' is provided with a central axially extending integral threaded nipple 86 which is screwed into the threaded upper end of the inner wall 18' of the pyrometer tube to effect a seal between the nipple 52', the upper end of inner wall 18', and the upper end of sleeve 80 which is integral with the outlet manifold. Such manifold is provided with an inwardly directed flange 88 which extends between the upper end of wall 18' and the shoulder portion surrounding nipple 86 on nipple 52'. Suitable packing material is provided between such flange and nipples 52', 86, and wall 18', so that upon the screwing down of nipple 52' a pressure tight joint is made between such parts.

Packing 84, previously described, is held under compression by the means shown in the central portion of Figure 7 and in Figure 8. Sleeve 80 is provided at a point beneath outlet manifold 49' with an outer threaded portion 90 on which is positioned the threaded nut 92. Interposed between nut 92 and gland 98, which surrounds the

sleeve and extends into contact with the packing, is a split clamp 94, the parts of which are held together around the sleeve by means of bolts 96. Upon the screwing down of nut 92, therefore, gland 98 may be forced to compress the packing 84 between outer wall 16' and sleeve 89 to effect a pressure tight seal. At the same time, however, sleeve 89 and consequently the upper end of inner wall 18' are free to move axially relative to the outer wall 16' upon heating of the pyrometer tube in service.

In Figure 7 there is shown a supply pipe 95 equipped with a shut-off valve 97 whereby a further cooling medium of a type different from that supplied by the source to which supply pipe 24' is connected may be delivered to the pyrometer tube. In some instances it is preferred to introduce compressed air into the cooling medium through pipe 95, the main cooling medium being water introduced through pipe 24'. Such air, which is introduced at a pressure in excess of that at which the water is supplied, mixes with the water flowing into the pyrometer tube cooling jackets so as to agitate the water stream continuously by the air bubbles passing through it, thereby keeping impurities in the water mixed therewith and in suspension, and preventing their attachment to the interior surfaces of the water passages. Such arrangement, which has been found particularly valuable where the cooling water supplied is frequently dirty, eliminates or greatly reduces the need for periodic cleaning of the cooling jackets.

Figures 9 and 10 show two further modifications of the pyrometer tube, the differences between such modifications and those previously described residing in the means by which the outer and inner cooling spaces between the outer and inner walls of the tube are formed. In Figure 9, which is a view in cross section through the lower portion of the modified pyrometer tube, there is provided a double walled tube having an outer wall 100 and an inner wall 102, the space between such walls being divided by a ribbed dividing tube 104, the ribs extending radially from the inner and outer surface of the dividing tube as shown and longitudinally thereof in an axial direction. Outer ribs 106, of which three are shown equally spaced about tube 104, correspond in function and in axial extent to the long corrugation 68 of the dividing tube 66 of the first modification above described. Intermediate between adjacent ribs 106 are a plurality of equally spaced ribs 108 corresponding in function and axial extent to the shorter corrugations 70 on the dividing tube 66 of the first modification. Tube 104 is provided with a plurality of equally spaced radial projections 110 for the division of the inner cooling space into equal axially extending sections to insure uniformity of cooling.

In the still further modification shown in Figure 10 division of the inner and outer cooling spaces between the outer wall 112 and the inner wall 114 of the double walled pyrometer tube is accomplished by providing both the outer surface of the inner wall 114 and the outer surface of dividing tube 116 with a plurality of outwardly radially described axially extending projections. Three of such projections shown as 118 are equally spaced thereabout and correspond in function and in axial extent to the corrugations 68 in the first modification above described. The other outer projections 120 on the dividing tube equally spaced between projections 118, as well as projections 122 on the inner wall 114, are of shorter

extent axially, since they correspond to corrugations 70 in the first modification and serve to divide the lower parts of the inner and outer cooling spaces equally circumferentially of the tube.

Two still further modifications of the cooling jacket structure of the pyrometer tube are shown in Figures 11 and 12. In some instances it has proved desirable to cause the cooling fluid in the inner and outer cooling jackets of the tube to travel in directions other than purely axially of the tube. In Figure 11 the cooling fluid, such as water, is caused to flow through the inner and outer cooling spaces in helical paths by providing a dividing tube 128 positioned between outer wall 124 and inner wall 126 with helical corrugations or ribs, corrugations being shown in the drawing. Certain of such corrugations or ribs 132 equally spaced circumferentially about the dividing tube are provided at their upper ends with axial corrugations or ribs dividing the upper portion of the outer cooling space into equal zones. The remainder of such corrugations or ribs 130 are made without such upper extensions and serve to divide such large cooling zones into smaller equal zones.

In Figure 12 the water within the cooling spaces is caused to travel in a sinuous direction by the provision of dividing tube 138 between outer wall 134 and inner wall 136, said dividing tube being provided with a plurality of equally spaced sinuous corrugations or ribs extending generally axially of the tube, corrugations being shown in the drawing. As in the case of previous modifications, certain of said corrugations or ribs 142 equally spaced circumferentially of the tube are made longer than the other corrugations or ribs 140. Such increased length is provided by straight corrugations or ribs joining with the tops of corrugations or ribs 142 for the purpose of dividing the cooling spaces in the plurality of equal zones, the other corrugations 140 serving to equal a plurality of smaller equal zones.

In some instances, as where the pyrometer tube of the present invention is used under particularly extreme conditions and is subjected to very high temperatures, it has proved desirable to provide it on its outer and lower surface thereof with an insulating layer to retard the flow of heat thereinto. In Figure 13 the lower end of the pyrometer tube so made is shown, the tube consisting of an outer wall 144, an inner wall 146, and a corrugated dividing tube 148. On the outer surface of wall 144 and on the lower end of the double wall there are provided a plurality of spaced projections 150, which may be in the form of studs welded to the outer tube wall. A layer 152 of high temperature insulating material, which is capable of withstanding temperatures to which the exterior of the inner end of the pyrometer tube is exposed, is applied to the outer surface of the outer wall 144 and a layer 154 of insulating material is applied at the bottom of the double walled tube as shown, studs 150, which are embedded therein, serving to hold the insulation firmly on the tube.

It will be apparent from the foregoing description that in the preferred method of cooling the tube of the present invention, in which the cooling medium flows first into contact with the outer hotter wall of the tube and thence into contact with the inner cooler wall thereof, such medium is introduced, in the modification first described, through pipe 24 to manifold 22, from which it flows through the spaced holes 26 into the upper portion of the outer cooling space. The water

then flows downwardly axially of the tube within the equal zones defined by the long ribs or corrugations from the manifold, the openings therefrom into the outer cooling space and the dividing corrugations or ribs being so constructed and arranged that equal volumes of water flowing at equal velocities are in contact with the outer wall of the tube at all points. The further shorter equally spaced corrugations or ribs insure that such condition is maintained throughout the entire length of the outer cooling space and also upon the return flow of the water in contact with the inner cooler wall. The division of the outer and inner cooling spaces in the manner described provides a plurality of passages in which the cooling fluid flows in thin sheets at a high velocity, thereby continuously scouring off the thin layer of steam or stagnant heated water which would otherwise tend to form in contact with the heated surface of the tube walls.

The manner in which the flow of cooling medium accomplishes this result is illustrated schematically in Figures 14 and 15 in connection with the operation of the first modification of the pyrometer tube. The downwardly flowing cooling stream of water W in the outer cooling space between the outer wall 16 and the dividing tube 66 is constantly met in its downward travel with the rising currents R of hot water from the inner wall of the outer tube 16. Such stream W, which travels at high speed, tends constantly to shear such rising currents R from the wall 16, causing them to intimately mix with the incoming water. At the same time steam bubbles S are also removed from the tube wall and are uniformly distributed through the cooling water so that they are caused to be condensed, thereby preventing any local accumulation of steam in the cooling jacket with resultant steam binding of the cooling system. When the corrugated dividing tube 66 is employed, the curve of such corrugations causes a further agitation of the cooling medium and a mixing of the incoming cooling water and the layer of hot water and steam coming off the tube wall. As shown in Figure 15, in a horizontal section of a portion of the pyrometer tube, such heated water and steam tend to travel laterally in each division of the outer cooling space in the directions indicated by the arrows R'. When the stream of cooling fluid W impinges upon such currents R', a very thorough mixing of the hot and cold water results with a consequent efficient removal of heat from the outer tube wall. The same thorough mixing of relatively cool and heated water and steam takes place in the inner cooling space, the direction of the relatively cool water in its return flow being indicated by the arrow W'.

The pyrometer tube made in accordance with the present invention is characterized by the ease with which it may be disassembled for cleaning when necessary, as well as by the advantages as to uniformity of cooling, absence of steam binding, and the maintenance of a clear sight line, above set out. Thus, in the modification shown in Figures 2 to 6, inclusive, the tube may readily be disassembled, after the disconnection of the inlet and outlet cooling medium tubes and the removal of the pyrometer tubes from the furnace by removing the bolts holding flanges 20, 30 and 38, 48 together. Thereupon plate 48 may be unscrewed from the upper end of inner wall 18 of the double walled tube, and joint 28 and dividing tube 66 lifted out for inspection and cleaning. The modification shown in Figures 7 and 8 may likewise be easily disassembled when desired.

This is effected by the loosening of nut 92, and of clamp 94, the inlet and outlet cooling tubes having been disconnected and the pyrometer tube removed from the furnace, so that sleeve 80, and consequently dividing tube 66' may be pulled axially out of the pyrometer tube.

Having thus fully described and illustrated preferred embodiments of the heat exchanger and more particularly the water-cooled pyrometer tube disclosed as a specific example of the present invention, I now desire to claim as new the following.

I claim:

1. A tubular heat exchanger comprising a double walled tube having an outer wall and an inner wall spaced radially therefrom to provide a heat exchanging medium receiving space between them, means joining the outer and inner walls of the tube at one end thereof to form a fluid tight joint, a dividing tube in the space between the tube walls to separate the space into an inner and an outer compartment each extending longitudinally of the tube, said tube extending to a point in the region of but somewhat spaced from the juncture between the inner and outer tube walls where the compartments join, means substantially to divide the inner and outer compartments into generally axially extending subcompartments, means to direct fluid into one of the compartments in a direction toward the closed end of the double walled tube in such manner as to provide a predetermined quantity of fluid at a predetermined velocity in each sub-compartment thereof, and means to exhaust the fluid from the other compartment in a direction away from the closed end of the double walled tube in such manner as to provide a predetermined quantity of fluid at a predetermined velocity in each sub-compartment thereof, said last two named means comprising means at a point remote from the joined ends of the double walled tube to form a seal between the outer tube wall and the dividing tube, means at a point remote from the joined ends of the double walled tube joined to the dividing tube to form a seal between the inner tube wall and the dividing tube, a manifold about the outer tube wall near the first sealing means, a series of passages through the outer tube wall within the manifold communicating with the outer compartment, a second manifold about the means joined to the dividing tube, and a series of passages through the means joined to the dividing tube within the second manifold communicating with the inner compartment.
2. A tubular heat exchanger comprising a double walled tube having an outer wall and an inner wall spaced radially therefrom, means joining the outer and inner walls of the tube at one end thereof to form a fluid tight joint, an intermediate single-walled dividing tube to divide the space between the tube walls to separate such space into an inner and an outer compartment, each extending longitudinally of the tube to a point in the region of but somewhat spaced from the juncture of the inner and outer tube walls where the compartments join, means substantially to divide the inner and outer compartments into axially extending sub-compartments, means to direct fluid into one of the compartments in a direction toward the closed end of the double walled tube in such manner as to provide substantially equal quantities of fluid at substantially the same velocity in each sub-compartment thereof, and means to exhaust the fluid from the other compartment in a direction away from the

closed end of the double walled tube in such manner as to provide substantially equal quantities of fluid at substantially the same velocity in each sub-compartment thereof, said last named means comprising means joined to the dividing tube at a point remote from the joined ends of the double walled tube to form a seal between the outer tube wall and the dividing tube and to form a seal between the inner tube wall and the dividing tube, said last-mentioned means including spaced flexible diaphragms and a fluid-exhausting manifold located between said diaphragms.

3. A tubular heat exchanger comprising a double walled tube having an outer wall and a substantially coaxial inner wall spaced radially therefrom to provide a heat exchanging medium receiving space between them, means joining the outer and inner walls of the tube at one end thereof to form a fluid tight joint, a dividing tube in the space between the tube walls to separate the space into an inner and an outer compartment each extending longitudinally of the tube, said tube extending to a point in the region of but somewhat spaced from the juncture between the inner and outer tube walls where the compartments join, means substantially to divide the inner and outer compartments into generally axially extending sub-compartments, means to direct fluid into one of the compartments in a direction toward the closed end of the double walled tube in such manner as to provide substantially equal quantities of fluid at substantially the same velocity in each sub-compartment thereof, and means to exhaust the fluid from the other compartment in a direction away from the closed end of the double walled tube in such manner as to provide substantially equal quantities of fluid at substantially the same velocity in each sub-compartment thereof, said last two named means comprising means at a point remote from the joined ends of the double walled tube to form a seal between the outer tube wall and the dividing tube, means at a point remote from the joined ends of the double walled tube joined to the dividing tube to form a seal between the inner tube wall and the dividing tube, a manifold about the outer tube wall near the first sealing means, said manifold being of volute shape and having a conduit connected thereto at the location of maximum cross-section, a series of equally spaced passages through the outer tube wall within the manifold communicating with the outer compartment, a second manifold about the means joined to the dividing tube, said manifold being of volute shape and having a conduit connected thereto at the location of maximum cross-section, and a series of equally spaced passages through such means joined to the dividing tube within the second manifold communicating with the second compartment.

4. A tubular heat exchanger comprising a double walled tube having an outer wall and an inner wall coaxial thereof and spaced radially therefrom, means joining the outer and inner walls of the tube at one end thereof to form a fluid tight joint, an intermediate dividing tube to divide the space between the tube walls to separate such space into an inner and an outer compartment, each extending longitudinally of the tube to a point in the region of but somewhat spaced from the juncture of the inner and outer tube walls where the compartments join, means substantially to divide the inner and outer compartments into axially extending sub-compartments, means to direct fluid into one of the compartments in a

direction toward the closed end of the double walled tube in such manner as to provide substantially equal quantities of fluid at substantially the same velocity in each sub-compartment thereof, and means to exhaust the fluid from the other compartment in a direction away from the closed end of the double walled tube in such manner as to provide substantially equal quantities of fluid at substantially the same velocity in each sub-compartment thereof, said last named means comprising means generally in the form of a tubular extension joined to the dividing tube at a point remote from the joined ends of the double walled tube to form a seal between the outer tube wall and the dividing tube and to form a seal between the inner tube wall and the dividing tube, said tubular extension being provided with a flexible diaphragm between the dividing tube and its point of connection to the outer wall of the double walled tube and with a flexible diaphragm between the dividing tube and its point of connection to the inner wall of the double walled tube to permit longitudinal expansion or contraction of the outer and inner tube walls relative to each other, said fluid-exhausting means being disposed between said flexible diaphragms.

5. A tubular heat exchanger comprising a double walled tube having an outer wall and an inner wall coaxial thereof and spaced radially therefrom, means joining the outer and inner walls of the tube at one end thereof to form a fluid tight joint, an intermediate dividing tube to divide the space between the tube walls to separate such space into an inner and an outer compartment, each extending longitudinally of the tube to a point in the region of but somewhat spaced from the juncture of the inner and outer tube walls where the compartments join, means substantially to divide the inner and outer compartments into axially extending sub-compartments, means to direct fluid into one of the compartments in a direction toward the closed end of the double walled tube in such manner as to provide substantially equal quantities of fluid at substantially the same velocity in each sub-compartment thereof, and means to exhaust the fluid from the other compartment in a direction away from the closed end of the double walled tube in such manner as to provide substantially equal quantities of fluid at substantially the same velocity in each sub-compartment thereof, said last two named means comprising means generally in the form of a rigid tubular extension joined to the dividing tube at a point remote from the joined ends of the double walled tube to form a seal between the outer tube wall and the dividing tube and rigidly joined to the inner tube wall to form a seal between the inner tube wall and the dividing tube, the tubular extension having one end in telescoped relationship with the end of the outer wall of the double walled tube, and a packing means between the tubular extension and the outer wall permitting longitudinal movement of the extension relative to the outer wall to permit longitudinal expansion or contraction of the outer and inner tube walls relative to each other.

6. A fluid-cooled tube comprising a main body made up of a double walled tube having an outer wall and an inner wall spaced radially therefrom to provide a heat exchanging medium receiving space between them, there being an unobstructed bore within the inner wall of the tube to provide a line of sight through the tube means joining the outer and inner walls of the tube

at one end thereof to form a fluid tight joint, a dividing tube in the space between the tube walls to separate the space into an inner and an outer compartment each extending longitudinally of the tube, said tube extending to a point in the region of but somewhat spaced from the juncture between the inner and outer tube walls where the compartments join, means substantially to divide the inner and outer compartments into generally axially extending sub-compartments, means to direct cooling fluid into one of the compartments in a direction toward the closed end of the double walled tube in such manner as to provide substantially equal quantities of fluid at substantially the same velocity in each sub-compartment thereof, means to exhaust the fluid from the other compartment in a direction away from the closed end of the double walled tube in such manner as to provide substantially equal quantities of fluid at substantially the same velocity in each sub-compartment thereof, means to introduce purging gas into the bore within the inner wall of the double walled tube in a direction toward the joint between the inner and outer walls thereof, an annular projection inwardly of the bore from the point of application of the purging gas and at least one passage immediately inwardly of the annular projection to allow the escape of gas therefrom.

7. A fluid-cooled tube comprising a main body made up of a double walled tube having an outer wall and an inner wall spaced radially therefrom to provide a heat exchanging medium receiving space between them, there being an unobstructed bore within the inner wall of the tube to provide a line of sight through the tube means joining the outer and inner walls of the tube at one end thereof to form a fluid tight joint, a dividing tube in the space between the tube walls to separate the space into an inner and an outer compartment each extending longitudinally of the tube, said tube extending to a point in the region of but somewhat spaced from the juncture between the inner and outer tube walls where the compartments join, means substantially to divide the inner and outer compartments into generally axially extending sub-compartments, means to direct cooling fluid into one of the compartments in a direction toward the closed end of the double walled tube in such manner as to provide substantially equal quantities of fluid at substantially the same velocity in each sub-compartment thereof, and means to exhaust the fluid from the other compartment in a direction away from the closed end of the double walled tube in such manner as to provide substantially equal quantities of fluid at substantially the same velocity in each sub-compartment thereof, said last named means comprising means at a point remote from the joined ends of the double walled tube to form a seal between the outer tube wall and the dividing tube, means at a point remote from the joined ends of the double walled tube joined to the dividing tube to form a seal between the inner tube wall and the dividing tube, a manifold about the outer tube wall near the first sealing means, a series of passages through the outer tube wall within the manifold communicating with the outer compartment, a second manifold about the means joined to the dividing tube, a series of passages through such means joined to the dividing tube within the second manifold communicating with the inner compartment,

and means to introduce purging gas into the bore within the inner wall of the double walled tube in a direction toward the joint between the inner and outer walls thereof.

5 8. A fluid-cooled tube comprising a main body made up of a double walled tube adapted to be mounted so that its forward end projects through a wall of a furnace, said tube having an outer wall and an inner wall coaxial thereof and spaced radially therefrom, there being an unobstructed bore within the inner wall of the tube to provide a line of sight through the tube means joining the outer and inner walls of the tube at the forward end thereof to form a fluid tight joint, an intermediate dividing tube to divide the space between the tube walls to separate such space into an inner and an outer compartment, each extending longitudinally of the tube to a point in the region of but somewhat spaced from the juncture of the inner and outer tube walls where the compartments join, means substantially to divide the inner and outer compartments into axially extending sub-compartments, means to direct cooling fluid into one of the compartments in a direction toward the closed end of the double walled tube in such manner as to provide substantially equal quantities of fluid at substantially the same velocity in each sub-compartment thereof, means to exhaust the fluid from the other compartment in a direction away from the closed end of the double walled tube in such manner as to provide substantially equal quantities of fluid at substantially the same velocity in each sub-compartment thereof, said last named means comprising means joined to the dividing tube at a point remote from the joined ends of the double walled tube to form a seal between the outer tube wall and the dividing tube and to form a seal between the inner tube wall and the dividing tube, said last named means each including a flexible diaphragm, one on each side of the fluid-exhaust means to permit expansion or contraction of the outer and inner tube walls relative to each other while maintaining the seals, and means to introduce purging gas into the bore within the inner wall of the double walled tube in a direction toward the forward end of the tube adapted to be positioned inside the furnace.

9. A fluid-cooled tube comprising a main body made up of a double walled tube adapted to be mounted so that its forward end projects through a wall of a furnace, said tube having an outer wall and an inner wall spaced radially therefrom to provide a heat exchanging medium receiving space between them, there being an unobstructed bore within the inner wall of the tube to provide a line of sight through the tube means joining the outer and inner walls of the tube at the forward end thereof to form a fluid tight joint, a dividing tube in the space between the tube walls to separate the space into an inner and an outer compartment each extending longitudinally of the tube, said tube extending to a point in the region of but somewhat spaced from the juncture between the inner and outer tube walls where the compartments join, means substantially to divide the inner and outer compartments into generally axially extending sub-compartments, means to direct cooling fluid into one of the compartments in a direction toward the closed end of the double walled tube in such manner as to provide substantially equal quantities of fluid at substantially the same velocity in each sub-compartment thereof, and means to

exhaust the fluid from the other compartment in a direction away from the closed end of the double walled tube in such manner as to provide substantially equal quantities of fluid at substantially the same velocity in each sub-compartment thereof, said last named means comprising means at a point remote from the joined ends of the double walled tube to form a seal between the outer tube wall and the dividing tube, means at a point remote from the joined ends of the double walled tube joined to dividing tube to form a seal between the inner tube wall and the dividing tube, a manifold about the outer tube wall near the first sealing means, said manifold being of volute shape and having a conduit connected thereto at the location of maximum cross-section, a series of equally spaced passages through the outer tube wall within the manifold communicating with the outer compartment, a second manifold about the means joined to the dividing tube, said manifold being of volute shape and having a conduit connected thereto at the location of maximum cross-section, a series of equally spaced passages through such means joined to the dividing tube within the second manifold communicating with the second compartment, and means to introduce purging gas into the bore within the inner wall of the double walled tube in a direction toward the forward end of the tube adapted to be positioned inside the furnace.

10. A fluid-cooled tube comprising a main body made up of a double walled tube adapted to be mounted so that its forward end projects through a wall of a furnace, said tube having an outer wall and an inner wall coaxial thereof and spaced radially therefrom, there being an unobstructed bore within the inner wall of the tube to provide a line of sight through the tube means joining the outer and inner walls of the tube at the forward end thereof to form a fluid tight joint, an intermediate dividing tube to divide the space between the tube walls to separate such space into an inner and an outer compartment, each extending longitudinally of the tube to a point in the region of but somewhat spaced from the juncture of the inner and outer tube walls where the compartments join, means substantially to divide the inner and outer compartments into axially extending sub-compartments, means to direct cooling fluid into one of the compartments in a direction toward the closed forward end of the double walled tube in such manner as to provide substantially equal quantities of fluid at substantially the same velocity in each sub-compartment thereof, means to exhaust the fluid from the other compartment in a direction away from the closed forward end of the double walled tube in such manner as to provide substantially equal quantities of fluid at substantially the same velocity in each sub-compartment thereof, said last named means comprising means generally in the form of a rigid tubular extension joined to the dividing tube at a point remote from the forward end of the double walled tube to form a seal between the outer tube wall and the dividing tube and rigidly joined to the inner tube wall to form a seal between the inner tube wall and the dividing tube, the tubular extension having one end in telescoped relationship with the rearward end of the outer wall of the double walled tube, a packing means between the tubular extension and the outer wall permitting longitudinal movement of the extension relative to the outer wall to permit expansion or contraction of the outer and inner tube walls relative to each other, and means to introduce purging gas into the bore within the inner wall of the double walled tube in a direction toward the forward end of the tube.

55

12. A fluid-cooled tube comprising an outer barrel, an inner tube extending rearwardly through and beyond the barrel coaxially thereof from the forward end and joined therewith continuously around said end, a tubular baffle extending into the barrel from the rear end thereof between the barrel and inner tube and terminating short of the junction thereof, an inlet manifold surrounding the barrel adjacent the rear end, flanges adjacent the rear ends of said barrel and tube, flexible diaphragms extending from said flanges to the end of said baffle projecting exteriorly of the barrel, and an outlet manifold surrounding said baffle between said diaphragms, said manifolds having ports communicating, respectively, with the spaces outside and inside the baffle.

13. The tube defined by claim 12 characterized by said baffle having ribs spaced circumfer-

or contraction of the outer and inner tube walls relative to each other, and means to introduce purging gas into the bore within the inner wall of the double walled tube in a direction toward the forward end of the tube, said fluid-exhaust means being between said diaphragms.

11. A fluid-cooled tube comprising a main body made up of a double walled tube adapted to be mounted so that its forward end projects through a wall of a furnace, said tube having an outer wall and an inner wall coaxial thereof and spaced radially therefrom, there being an unobstructed bore within the inner wall of the tube to provide a line of sight through the tube means joining the outer and inner walls of the tube at the forward end thereof to form a fluid tight joint, an intermediate dividing tube to divide the space between the tube walls to separate such space into an inner and an outer compartment, each extending longitudinally of the tube to a point in the region of but somewhat spaced from the juncture of the inner and outer tube walls where the compartments join, means substantially to divide the inner and outer compartments into axially extending sub-compartments, means to direct cooling fluid into one of the compartments in a direction toward the closed forward end of the double walled tube in such manner as to provide substantially equal quantities of fluid at substantially the same velocity in each sub-compartment thereof, means to exhaust the fluid from the other compartment in a direction away from the closest forward end of the double walled tube in such manner as to provide substantially equal quantities of fluid at substantially the same velocity in each sub-compartment thereof said last named means comprising means generally in the form of a rigid tubular extension joined to the dividing tube at a point remote from the forward end of the double walled tube to form a seal between the outer tube wall and the dividing tube and rigidly joined to the inner tube wall to form a seal between the inner tube wall and the dividing tube, the tubular extension having one end in telescoped relationship with the rearward end of the outer wall of the double walled tube, a packing means between the tubular extension and the outer wall permitting longitudinal movement of the extension relative to the outer wall to permit expansion or contraction of the outer and inner tube walls relative to each other, and means to introduce purging gas into the bore within the inner wall of the double walled tube in a direction toward the forward end of the tube.

entially thereof forming passages therealong of substantially equal sectional area.

14. The tube defined by claim 13 characterized by said ribs being staggered between the manifold ports.
